DISPENSING CIGARETTE CASE

Joseph P. Zaidan, Philadelphia, Pa.

Application November 6, 1946, Serial No. 708,137

2 Claims. (Cl. 206—41.2)

1

This invention relates to cigarette cases.

It is an object of this invention to provide an improved cigarette case of the kind to be more particularly described hereinafter having a spring-pressed ejector for moving certain of the cigarettes in a package upwardly from the pack where they may readily be reached by the user without the usual trouble of trying to grip the upper end of one cigarette to remove it from the package.

Another object of this invention is to provide an improved cigarette case of this kind wherein the package of cigarettes as normally sold to the purchaser in a paper package may be readily inserted into the case and prepared for the operation of the ejector by merely tearing an upper and a lower corner of the paper package before inserting the entire package into the case.

Still another object of this invention is to provide an improved cigarette case of this kind which is formed of a minimum number of parts and is so constructed and arranged to provide for ready forming and assembling by mass production methods, thus providing for a low cost of manufacturing whereby the benefits of such construction may be passed to the purchaser in the form of a very efficient low-priced cigarette case having the service of the more intricate, complexly composed, more expensive cigarette cases of this kind on the market.

With the above and other objects in view, my invention consists in the arrangement, combination and details of construction disclosed in the drawings and specification, and then more particularly pointed out in the appended claims.

In the drawings,

Figure 1 is a top plan view of a cigarette case constructed according to an embodiment of this invention.

Figure 2 is a vertical section of the case, taken on the line 2—2 of Figure 1.

Figure 3 is a vertical section taken on the line 3—3 of Figure 2.

Figure 4 is a transverse section taken on the line 4—4 of Figure 2.

Figure 5 is a fragmentary side elevation of the upper end of the cigarette case, the cover and ejector being removed.

Referring to the drawings, the numeral 10 designates generally a cigarette case, having a spring-pressed ejector, constructed according to an embodiment of this invention. The case 10 is formed of a rectangular body 11 having an open upper end. The body 11 is of sufficient size and dimensions to snugly enclose a package of ciga-

2

rettes as normally sold in paper packages of twenty, and is preferably made of aluminum or other suitable material to preserve the shape of the package and the cigarettes therein when the case may be carried in the pocket of the user, though other materials as plastic may be preferred by certain manufacturers and sellers. The upper edges of the body 11 are cut away on one end of the upper edge and along the sides from the reduced end partially along the length of both sides of the body to provide a recess in which the slideable cover 12 engages whereby the upper surface of the cover 12 is substantially flush with the upper edge of the body 11.

The cover 12 is formed of a U-shaped strip of material having a closed outer end and an open inner end, the downwardly extending arms 14 of the cover forming flanges which overlie the sides of the body with which the cover engages. The body 11 is further formed with an elongated slot 15 near to and parallel with the upper edge thereof near one end of both sides to provide a guide in which the cover 12 engages to hold the cover from being inadvertently removed. A vertically extending slot 16 communicates with the slot 15 near the outer edge thereof and opens upwardly from the upper edge of the sides of the body 11. Pins or detents 17 are fixed to the opposite sides of the cover 12 and extend inwardly therefrom. The pins 17 are adapted to slidably engage in the slots 15 and 16 for slidably securing the cover 12 to the body 11.

A spring-pressed cigarette ejector 18 is slidably secured in the case 10 on one side opposite from the side on which the cover 12 engages, and is provided for raising certain ones of the cigarettes at that end of the case upwardly from the level of the package to a point where the upper end of these certain cigarettes may be readily reached by a user without damaging the cigarette.

The ejector 18 is formed of a flat piece of metal substantially L-shaped, of a width slightly less than the width of the end of the body 11 so the ejector may slide on one side wall of the body. The lower horizontal arm 19 of the ejector extends inwardly from the end wall a short distance to underlie a certain number of cigarettes and engages over the free inner end of the shelf 20 fixed in the case. The shelf 20 is fixed in the body 11 parallel to and spaced upwardly from the bottom thereof and extends nearly across the width of the case. The shelf 20 is formed with an elongated slot 21 at its inner free end which extends part way to the side wall of the case 10 opposite from the ejector 18 to permit the spring 22 to

press the ejector upwardly. The spring 22 is formed of a flat resilient strip of metal and is fixed at one end to the bottom of the body 11 by engaging through the bottom wall and the free end of the spring engages the under side of the arm 19 of the ejector 18 between the sides of the slot 21, the normal or released position of the spring being shown in dotted lines in Figure 2.

The vertical arm 24 of the ejector 18 lies flat against the end wall of the body 11 and is slidably secured thereto by a screw 25 which engages through the vertically extending slot 26 in the end wall. The head or outer end of the screw 25 is provided with an enlarged head or handle 27 which the operator may readily engage with a finger for retracting the ejector after use. The length of the vertical arm 24 is substantially equal to the length of the end wall from the shelf 20 to the upper edge of the body 11.

A second cover or closure 28 is hingedly secured to the upper end of the arm 24 and normally extends inwardly of the body 11 parallel to the lower arm 19 of the ejector 18. The cover 28 is provided for covering that end of the case and those cigarettes on the arm 19 of the ejector in the closed position of the case 10 which will rise from the case as the case is opened. The cover 28 is adapted to lie flush with the upper edges of the body 11, in its closed position, and the free end is of a length sufficient to lie under the free open end of the cover 12, in its closed position, to completely close and seal the upper open end of the body 11.

In the use and operation of this case 10, a paper package of cigarettes 30 should be torn at the upper and lower corners on the top and side of one end, as more clearly shown in Figure 2. The cover 12 is removed completely from the body 11 and the package 30 inserted into the case with the upper torn corner adjacent the hinge 31 of the open cover 28, the opened cover being shown in dotted lines in Figure 2. The cover 28 is then moved closed and the slider 27 is pressed downwardly so the cover 12 may be placed back on the body 11 with the pins or detents slidably engaging in the slots 15, and having the open inner end overlying the inner end of the closure 28. When the case 10 is used to dispense cigarettes, the cover 12 is slid outwardly in the slots 15 by the finger of an operator engaging the handle 34 on the upper side thereof, whereupon the spring 22 presses the ejector 18 upwardly a short distance to raise certain cigarettes upwardly from the case, and the cover 28 is readily moved out of the way. For restoring the case 10 to position for ejecting other cigarettes, the user merely moves the cover 28 inwardly, presses the head 27 downwardly and

slides the cover 12 back to engage over the inner end of the cover 28. The normal bouncing around of the case 10 is usually sufficient to move other cigarettes on to the arm 19 of the ejector 18, and when the supply is nearly exhausted the case may be tilted and the cigarettes in the case will fall into place on the ejector 18.

I do not mean to confine myself to the exact details of construction herein disclosed, but claim all variations falling within the purview of the appended claims.

What I claim is:

1. A cigarette case of the kind described comprising a body having an open upper end, an L-shaped ejector in said body on one side thereof, resilient means constantly urging said ejector upwardly in said body, a sliding cover on one side of said body opposite from said ejector, a hinged cover on the upper end of said ejector, said hinged cover partially underlying said sliding cover in the closed position thereof whereby said ejector is restrained in said case in the closed position of said sliding cover and is urged upwardly to extend from said case upon sliding of said sliding cover to the open position.

2. A cigarette case comprising a hollow body having an open upper end, a sliding cover for closing a part of said open end, means slidably securing said sliding cover on said body, an ejector slidably mounted in said body on one side thereof opposite from said sliding cover, spring means urging said ejector upwardly in said body for raising cigarettes thereon upwardly from said body, a hinged closure on the upper end of said ejector, said sliding closure partially overlying the inner end of said hinged closure for restraining said ejector in said body in the closed position of said sliding closure whereby said ejector is free to slide upwardly in said body upon movement of said 40 sliding closure to open position.
